UNITED STATES PATENT OFFICE

WILLIAM SCHNELL AND BONNIE E. LEMM, OF DETROIT, MICHIGAN, ASSIGNORS TO TERNSTEDT MANUFACTURING COMPANY, OF DETROIT, MICHIGAN, A CORPORATION OF MICHIGAN

DESIGN FOR A DOOR HANDLE

Application filed October 12, 1929. Serial No. 33,024. Term of patent 7 years.

To all whom it may concern:

Be it known that we, WILLIAM SCHNELL and BONNIE E. LEMM, both citizens of the United States, respectively, residing at 5571 Clarendon Avenue, Detroit, in the county of Wayne and State of Michigan, and 1120 Campbell Avenue, Detroit, in the county of Wayne and State of Michigan, have invented a new, original, and ornamental Design for a Door Handle, of which the following is a specification, reference being made to the accompanying drawings, forming part thereof.

Fig. 1 is a front elevation of the door handle showing our new design.

Fig. 2 is a side elevation of the door handle.

We claim:

The ornamental design for a door handle substantially as shown.

WILLIAM SCHNELL.
BONNIE E. LEMM.
